(57) CLAIM

The ornamental design for a chair, as shown and described.

DESCRIPTION

FIG. 1 is a top, front, and left side perspective view of the chair, showing my new design;

FIG. 2 is a bottom, front, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the chair that form no part of the claimed design.

1 Claim, 8 Drawing Sheets(56)
